(57) **CLAIM**

The ornamental design for a seamless cornice fascia, as shown and described.

DESCRIPTION

FIG. 1 is a front and right side perspective view of a seamless cornice fascia, showing a first variant of my new design;

FIG. 2 is a right side view thereof, the left side view being a mirror image;

FIG. 3 is a top view thereof, the bottom view being a mirror image; and,

FIG. 4 is a front view thereof; the rear view being a mirror image.
